LATCH

William Lange, Rice Lake, Wis.

Application March 30, 1938, Serial No. 199,016

1 Claim. (Cl. 292—128)

This invention appertains to new and useful improvements in closure fasteners and more particularly to a latch which can be used for garage doors, closets and various other structures where closures are used.

Other important objects and advantages of the invention will become apparent to the reader of the following specification.

In the drawings—

10 Figure 1 represents a fragmentary side elevational view of a closure showing the fastener.

Figure 2 is a horizontal sectional view through the fastener.

15 Figure 3 is a vertical sectional view taken substantially on a line 3—3 of Figure 1.

Figure 4 is a perspective view of the fastener element.

Figure 5 is a fragmentary side elevational view of the outside of a closure showing the fastener.

20 Figure 6 is a sectional view taken substantially on a line 6—6 of Figure 3.

Figure 7 is a sectional view taken substantially on a line 7—7 of Figure 2.

25 Figure 8 is a horizontal sectional view taken substantially on a line 8—8 of Figure 1.

Figure 9 is a perspective view of the keeper plate.

Referring to the drawings, wherein like numerals designate like parts, it can be seen that 30 the numeral 5 represents the closure, while numerals 6—7 represent portions of the building structure at opposite sides of the door.

Extending through the door 5 is the outwardly flaring opening 8 through which extends the 35 shank 9, this shank 9 projecting laterally from the elongated latch rod 10 which at one end is bent outwardly as at 11 and longitudinally at 12 and inwardly at 13 to connect to itself as at 14 to form a handle A. The other end of the rod 10 is bent laterally as at 15 to form a neck and this 40 terminates in the arrow shaped head 16.

A pair of plates 17—17 are secured to the closure 5 by screws 18 and the intermediate portions of these plates are formed to provide barrels 19 in 45 which the rod 10 is journaled. As is shown in Figures 1 and 2, the portion 6 of the building structure is provided with the recess 20 over which is disposed the plate 21, this plate being provided with openings for receiving the securing elements 22 and also with the rectangular shaped opening 23 stamped to provide the tongue 24

which inclines into the recess 20, and over which the arrow shaped head is engageable as suggested in Figure 8.

To the outside of the closure 5 is secured the plate 25 having the vertically disposed pocket 26 formed therein and this plate 25 is secured to the door by screws 27. The upper portion of the pocket 26 is notched as at 28 to receive the rod shank 9, this shank 9 being provided with the threaded end portion 29 for engagement into the 10 knob 30.

A plate 31 is slidably disposed in the pocket structure 26 and has an opening therein for loosely receiving the rod shank 9. The lower end of this plate 31 has the upper end of the coiled extensible spring 32 connected thereto while the lower end of the spring 32 is anchored as at 33 to the bottom of the pocket 26. Thus it can be seen that the knob 30 is normally held downwardly and in the notch 28 by the spring 32, thus holding one side of the head 16 engaged with the lip 24 of the keeper plate 21. The door 5 may be opened by pushing downwardly on the handle 8 which will disengage the head from the keeper.

While the foregoing specification sets forth 25 the invention in specific terms, it is to be understood that numerous changes in the shape, size and materials may be resorted to without departing from the spirit and scope of the invention, as claimed hereinafter.

Having described the invention, what is claimed as new is—

A door latch comprising a longitudinally arranged rod journaled on one face of a door and having one end portion constructed to engage a 35 keeper and said rod being partially bent on itself to form a substantially rectangular shaped handle, a shank formed on said rod and extending at right angles thereto and through a slot in the door and including a door handle, a slidable plate 40 having an opening to receive the shank, a base plate secured on the door and having a pocket to slidably receive the slidable plate and provided with a notch, and a coil spring connecting the slidable plate and the base plate and lying within 45 the pocket to urge the slidable plate in a direction to position the shank in the notch for limiting the rotation of the rod in one direction, said rod being restricted in its rotation in an opposite direction by said spring.

50 WILLIAM LANGE.
